COAL DRILL MOUNT

Donald E. Bissell, James W. Bissell, and
Walter E. Bissell, Jasonville, Ind.

Application November 10, 1949, Serial No. 126,596

1 Claim. (Cl. 255—51)

1

This invention appertains to a coal mining machine and has for its primary object to enable blasting holes to be conveniently, efficiently and speedily drilled perpendicular in a coal face.

Another important object of this invention is to provide a drilling machine, especially designed and adapted for utilization in drilling blast holes, the machine being extremely maneuverable in operation, so that it may be easily and quickly positioned for operation in any desired relation to the coal face.

A further important object of this invention is to provide a portable support for a drilling mechanism and to mount the drilling mechanism on the support in such a manner that the mechanism is selectively adjustable and movable into various positions in plurality of directions and planes.

Yet another important object of this invention is to provide inexpensively constructed and maintained drilling apparatus, which can be adjusted manually with a minimum of manual labor.

These and ancillary objects and structural features of merit are attained by this invention, the preferred embodiment of which is set forth in the following description and illustrated in the accompanying drawings, wherein:

Figure 1 is a side elevational view of the portable drilling apparatus;

Figure 2 is a top plan view;

Figure 3 is an enlarged elevational view, with the drilling apparatus folded back in an inoperative position overlying the tram;

Figure 4 is an enlarged longitudinal sectional view of the supporting boom taken on line 4—4 of Figure 2;

Figure 5 is a transverse sectional view taken on line 5—5 of Figure 1;

Figure 6 is an enlarged sectional view taken on line 6—6 of Figure 1;

Figure 7 is a transverse sectional view taken on line 7—7 of Figure 1; and,

Figure 8 is a transverse sectional view taken on line 8—8 of Figure 2.

This invention relates to a portable drilling apparatus for drilling blast holes in a coal vein and generally consists of a portable tram, upon which a support is rotatably mounted in a vertical plane. The support receives a boom, which is rigidly attached thereto, so that the boom, which is horizontally disposed, can rotate on the tram through a horizontal arc of 360°. A support is mounted on the free end of the boom and also is capable of rotation through an arc of 360°. Vertically movable means is carried by the sup-

port on the boom and is actuated by hydraulic means, the vertical means supporting a drill motor bracket, which is pivotally mounted thereon. The drill driving mechanism, which is carried by the bracket, is, therefore, universally connected to the tram and supported thereby, so that the drill mechanism is adjustable in various directions and planes for operative positioning transverse to the vein or face of the coal or similar material.

Attention is now directed to the accompanying drawings, wherein it will be noted that a conventional tram or truck 10, which is mounted on wheels 12 is provided, the tram forming a stationary support for the drill driving mechanism 14, the mechanism being universally connected to the tram by means of the connecting means, generally designated as at 16.

A tubular post 18 is mounted on a horizontal base 20 which is superimposed on the upper face of the tram, so that the post is disposed perpendicular to the horizontal tram. Bearing assemblies 22 and 24 are disposed concentric to the post, at the opposing ends thereof, the lower assembly being seated on a collar 26 concentric to the lower end of the post. Tapered rollers or ball bearings 28 are employed in the bearing assemblies. A cylindrical support 30 is rotatably mounted on the bearing assemblies, the support being formed with vertically spaced annular shoulders 32 for receiving the bearing assemblies, as seen in Figure 4. An annular flange 34 is formed on the lower end of the cylindrical support, sealing means 36 being concentric on the collar 26 to seal the lower end of the support from the collar and sealing means 38 being provided at the upper end of the post for sealing the cylindrical support.

A boom 40 is rigidly secured to the cylindrical support and projects laterally therefrom, the boom being horizontally disposed and preferably consisting of an elongated square post. A plate 42 extends diagonally between the upper end of the cylindrical support and the post to enclose opening 44 in the boom and an opening 46 in the upper end of the cylindrical support.

It can be seen that the boom rigidly carried by the cylindrical support is rotatable about the vertical axis of the post 18. Locking means 48 is provided for locking the boom in a forwardly projecting position, as seen in Figure 2. The locking means includes a sleeve 50 which has its lower end welded or otherwise secured on the upper face of the flange 34. An upper sleeve 52 is disposed in alignment with the sleeve 50 and

the complementary edges of the sleeve are beveled as at 54 to form cam surfaces. A locking pin 56 is positioned within the aligned sleeve and secured to the upper sleeve 52 by lateral pins 58. The pin 56 projects through vertical openings 60 in the base 20 and a registerable vertical opening 62 in the flange, the opening 62 being aligned with the sleeve. The pin 56 terminates in an axially reduced upper end 64 which is vertically disposed through the horizontal section of an angle member 66, the member 66 being welded as at 68 to the boom. A spring 70 is disposed on the reduced end 64 and functions to yieldingly urge the pin into the opening 60 in the base. An arm 72 projects integrally from the upper sleeve section 52 and extends laterally therefrom, the arm being pivoted to an elongated operating rod 74. The opposing end of the rod is pivoted within the clevis end 76 of the bar 78 extending through a transverse slot 80 in the boom. A pin 82 is vertically disposed through the opposing end of the bar to retain the same within the transverse slot 80.

It can be seen that with the pin 56 inserted in the base, the boom is held against rotation about the post 18. However, a pull exerted on the bar 72 will produce a raising movement of the pin from the face, the upper sleeve 52 being raised by complementary cam edges and raising the pin against the urging of the spring. The boom can then be rotated either clockwise or counterclockwise and when the pin 56 overlies the opening 60 in the base, the spring will automatically return the pin to its locked keying position.

A base member 82 is mounted on the outer end of the boom and a cylindrical support 84 is concentrically disposed on a vertically positioned tubular post 86, the post being mounted on the base 82. Bearing assemblies 88 are disposed concentric on the post and spaced the vertical support from the post. An annular flange 90 is formed on the lower end of the support and overlies the base 82, locking means 92 being provided and engageable in the flange and base to lock the cylindrical members against rotation on the post. The locking means 92 consists of a sleeve 94 extending upwardly from the flange and aligned with the vertical opening 96 in the flange. A vertical opening 98 is formed in the base and is registerable with the opening in the flange to receive a locking pin 100, having an upper axially reduced end 102. A lateral bracket 104 projects from the supporting member and is formed with a vertical opening to receive the upper end of the pin. One end 106 of a bell crank 108 is secured on the end 102 of the pin and positioned thereon by a stop 110.

A pair of vertical support bars 112 and 114 are seated on the flange 90 and secured to the cylindrical supporting member 84, the bars being transversely spaced and having vertically spaced transversely disposed journal pins or rods 116 and 118 mounted therein. Collars 120 and 122 are rotatably disposed on the opposing projecting ends of the rod 118, the collars being held thereon in abutting engagement of spacers 124 engaging the outer surface of the supporting bars by securing caps 126. Elongated tubes 128 and 130 are secured to the collars and, in a similar manner, collars 132 are mounted on the extending ends of the pin 116 to support extending tubular members 134 and 136. The tubes 128 and 130 converge inwardly at their outer ends and are joined to a common collar 138, the tu-

bular members 134 and 136 being similarly positioned and joined to a collar 140. The collars 138 and 140 are vertically spaced and are rotatably disposed on supporting pins transversely disposed through the parallel walls 144 and 146 of a channel bar 148. The tubes 128 and 130 form chords of a triangular truss which also includes the collar 138 and the pivot pin 118 while the tubes 134 and 136 form the chords of a lower triangular truss which also includes the collar 140 and the pivot pin 116. The two trusses are in spaced parallel relation.

Brackets 156 and 152 are secured to the web of the channel bar and are vertically spaced thereon, the brackets supporting the drilling mechanism 14. The mechanism consists of a motor 158, which is preferably an electric motor actuated by electric current derived from flexible conductors 166 which extend through the post 18 and enter the boom through the openings 44 and 46 covered by the shield 42, as seen in Figure 4. A socket 158 is rotated by the motor and is adapted to receive a drill bit 160, with a positioning housing 162 for a lead screw (not shown) 20 of the drilling mechanism 14 projecting in opposite direction from the motor. A square sleeve 164 is secured by a plate 166 to the motor housing and a rod 168 is vertically disposed through the bracket 150 and is formed with enlarged upper 25 end 170 received within the sleeve and attaching the motor to the channel bar 148.

Hydraulic means is provided for raising and lowering the parallelogram support, consisting of the upper and lower triangular trusses, the hydraulic means being preferably manually actuated and consisting of an hydraulic double-acting motor 171 which includes a cylinder 172 which is formed at its closed end with a collar 174 rotatably journaled on the pin 116 between the bars 112 and 114. A piston rod 176 is workably mounted in the cylinder and is formed at its outer end with a transverse sleeve 178 positioned on the central portion of a rod 180 disposed transversely between a pair of complementary ears 182 carried by the tubes 128 and 130. A lateral connection 184 projects from the cylinder and flexible conduits 186 extend from the connection to a manually operated hydraulic pump 188. The pump is mounted on brackets 190 and 192 extending laterally from the tubular member 134.

As seen in Figure 1, the crank 108 is operated by an elongated rod 194, having its opposite end pivoted to a vertical bar 196 disposed between the tubes 128 and 134. The bar 196 is carried by one end of a shaft 198 which is journaled in a sleeve 200 carried by the tubes 128 and 130. The opposite end of the shaft 198 has rigidly secured thereto a handle 202 for operating the bar 196.

In operation, it can be seen that the boom can be rotated about the vertical post 18 and the parallelogram can be rotated about the vertical post 86 mounted on the outer end of the boom. The drilling mechanism proper can be vertically rotated by means of the pin 116, so that the drilling mechanism is universally mounted on and carried by the portable tram. Thus, the tram can be moved by the wheels 12 on the conventional tracks in a mine and the drilling mechanism can be operated, without moving the tram from the tracks, the drilling mechanism being extremely maneuverable and the maneuverability being manually controlled in a simple and convenient manner.

Having described the invention, what is claimed as new is:

In a mine drilling apparatus, a wheel mounted tram, a horizontal boom, a vertical post on said tram, a cylindrical member fixed to one end of said boom and rotatably mounted on said post, means for locking said member against rotation on said post, a turntable mounted on the outer end of said boom for rotation about a vertical axis, parallel triangular trusses having diverging chords connected at spaced ends by pivot pins, said pivot pins pivotally securing said trusses to said turntable in spaced relation, a vertical drill support pivotally connected to outer ends of said trusses, a hydraulic motor having one end connected to one of said pivot pins, the other end of said hydraulic motor being connected to the truss distant from said one pivot pin intermediately.

ate the ends of the last mentioned truss, said hydraulic motor being disposed between vertical planes passing through the chords of said trusses, and a hydraulic pump carried by one of said trusses operatively connected to said hydraulic motor.
